US00D837664S

(12) **United States Design Patent** (10) **Patent No.:** **US D837,664 S**
(45) **Date of Patent:** **** *Jan. 8, 2019**

(54) **TIMER**

(71) Applicant: **Yuan Mei Corp.**, Chang Hua Hsien (TW)

(72) Inventor: **Chi-Han Cheng**, Chang Hua Hsien (TW)

(73) Assignee: **Yuan Mei Corp.**, Chang Hua Hsien (TW)

(*) Notice: This patent is subject to a terminal disclaimer.

(**) Term: **15 Years**

(21) Appl. No.: **29/600,057**

(22) Filed: **Apr. 10, 2017**

Related U.S. Application Data

(63) Continuation of application No. 29/597,936, filed on Mar. 21, 2017.

(51) **LOC (11) Cl.** **10-03**

(52) **U.S. Cl.**

USPC **D10/40; D23/245**

(58) **Field of Classification Search**

USPC D10/40, 49, 56, 96, 125; D13/162.1; D16/200, 217, 218, 220; D23/245, 246

CPC A01G 25/00; A01G 25/16; A01G 25/165; B05B 12/02; F16K 31/48

(57) **CLAIM**

The ornamental design for a timer, as shown and described.

DESCRIPTION

FIG. 1 is a right front perspective view of a timer showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate portions of the timer that form no part of the claimed design.

1 Claim, 7 Drawing Sheets
